Seymour Sohn, 842 Jacon Way, Pacific Palisades, Calif.

Filed Jan. 27, 1961, Ser. No. 63,733

Term of patent 14 years

(Cl. D72—1)

FIG.1.

FIG.2.

FIG.3.

FIGURE 1 is a front elevational view of a warning signal for highways or the like illustrating my new design;

FIGURE 2 is a side elevational view thereof; and,

FIGURE 3 is a top plan view thereof.

The rear and side of the signal not shown are substantially the same in appearance as the front and side shown as indicated in FIGURES 2 and 3.

I claim:

The ornamental design for a warning signal for highways or the like, substantially as shown and described.
